LANTERN SLIDE FILE BOX

Arthur C. Rissberger, Jr., Rochester, N. Y., assignor to Eastman Kodak Company, Rochester, N. Y., a corporation of New Jersey

Application October 27, 1953, Serial No. 27,351

Term of patent 7 years

(Cl. D58—12)

To all whom it may concern:

Be it known that I, Arthur C. Rissberger, Jr., a citizen of the United States of America, residing at Rochester, in the county of Monroe and State of New York, have invented a new, original, and ornamental Design for a Lantern Slide File Box, of which the following is a specification, reference being had to the accompanying drawing, forming a part thereof, in which:

Fig. 1 is a top plan view of a lantern slide file box showing my new design;

Fig. 2 is a side elevational view thereof;

Fig. 3 is a bottom plan view thereof;

Fig. 4 is an end elevational view thereof;

Fig. 5 is an end elevational view thereof, taken from the side opposite to that of Fig. 4; and

Fig. 6 is a fragmentary detail sectional view thereof taken on the line 6—6 of Fig. 1.

I claim:

The ornamental design for a lantern slide file box, as shown.
